UNITED STATES PATENT OFFICE.

HERMAN F. BUSCH, OF MILLVALE, PENNSYLVANIA, ASSIGNOR TO ARMSTRONG CORK CO., OF PITTSBURGH, PENNSYLVANIA, A CORPORATION OF PENNSYLVANIA.

SPINNING AND DRAWING ROLL FOR TEXTILE OPERATIONS.

1,269,682.

Specification of Letters Patent. Patented June 18, 1918.

Application filed March 12, 1917. Serial No. 154,121.

To all whom it may concern:

Be it known that I, HERMAN F. BUSCH, a citizen of the United States, residing at Millvale, Allegheny county, Pennsylvania, have 5 invented a new and useful Improvement in Spinning and Drawing Rolls for Textile Operations, of which the following is a full, clear, and exact description, reference being had to the accompanying drawings, forming 10 part of this specification, in which—

Figure 1 is a plan view of one form of roll embodying my invention.

Fig. 2 is a section on the line II—II of Fig. 1.

15 My invention has relation to certain new and useful improvements in rolls of the character widely used in all textile spinning and drawing processes, and more particularly to the top rolls, and is generally applicable to all forms of such top rolls irrespective of their particular size and shape. Heretofore, top rolls of this class have been provided with a covering of leather secured to the metal body of the roll over a cloth 20 backing or lining, the latter acting as a cushion to increase the resiliency of the covering. Other covering materials have been tried, usually with but little success, leather being now almost universally employed.

25 30 I have discovered that greatly superior rolls may be obtained by providing them with a covering consisting of artificial cork.

Natural cork has not proven satisfactory for this purpose, apparently for the reason that it is not sufficiently homogeneous in 35 character and also because its surface soon becomes glazed to such an extent that it does not exert a proper frictional grip on the threads or fiber.

40 45 A covering of artificial cork such as is provided by my invention provides an extremely serviceable and durable roll having a wearing quality better than that of leather; which will work under less pressure than is required with leather covered rolls and which does not "pick up" fiber to nearly as great an extent as the leather coverings. The coverings provided by my invention can be readily and easily applied and renewed, 50 and possess the degree of resiliency and frictional qualities which are desirable for this work. Actual tests of my invention show that rolls provided with the improved covering pick up less than one-half the quantity of fiber that is picked up by leather covered rolls and only have to be cleared half

as often. An examination of such rolls which have been in continuous use for a period of nine months, gives no indication of wear. The increased life of the rolls 60 greatly reduces the number of reserve rolls which must be carried in stock by a mill.

65 In the accompanying drawings, the numeral 2 designates the steel body of one form of drawing roll having the reduced central portion 3 upon which rests the usual weight saddle, not shown. The enlarged end portions 4 of the roll are each provided with 70 my improved covering, shown at 5. These coverings consist of sheets of artificial cork. I prefer that these coverings shall be laminated and that they be formed by cutting the artificial cork into relatively thin strips which are then wound upon the rolls, one 75 layer over another until the requisite thickness is obtained. Preparatory to this winding, both surfaces of the strips are coated with any suitable glue or cement. After the winding is completed, the rolls are thoroughly baked in an oven at a suitable baking 80 temperature of say from 175° to 200° Fahrenheit. The covered portions are then turned or ground to the exact size desired. By making the coverings in laminated form in this manner, I not only avoid the necessity 85 for the use of any molding or clamping devices in applying the coverings to the rolls, but a superior covering is provided, as the laminated structure is less liable to give way 90 in service.

95 It is important that the artificial cork used should be of the proper character and density. I have obtained excellent results from a mixture consisting of one hundred pounds of granulated cork, twenty pounds 100 of glycerin and five pounds of gelatin. I also add about six ounces of paraformaldehyde in dry powdered form for the purpose of rendering the gelatin insoluble. These proportions may, however, be varied to a 105 considerable extent. The materials are thoroughly mixed after which they are pressed into a mold, sufficient pressure being preferably employed to reduce the mass to about one-eighth of its initial volume. The molds containing the material confined under pressure are then subjected to baking operations such as are customarily employed in the manufacture of artificial cork. The resulting blocks are then cut into strips of the desired width and thickness.

110 It is also important that the cork granules

employed in the mixture shall neither be too coarse nor too fine. I prefer to employ cork granules none of which has a dimension greater than three thirty-seconds of an inch and which will pass through a screen having eleven meshes to the inch. Preferably, also, none of the particles should be finer than No. 40 mesh. In practice, the bulk of the material is usually between sixteen and 10 twenty-eight mesh.

As before indicated, my invention is not limited for use in connection with the particular form of roll illustrated in the drawing, but is generally applicable to the forms of 15 spinning and drawing rolls used in textile operations.

I claim:

1. A roll having a covering of artificial 20 cork wound in convolute layers; substantially as described.

2. A roll having a covering of artificial cork wound in convolute layers, adjacent layers of the covering being cemented to each other, substantially as described.

3. A spinning and drawing roll having a 25 covering of artificial cork in thin sheet form wound upon itself in convolute layers, substantially as described.

4. A spinning and drawing roll having a 30 covering of artificial cork in thin sheet form wound upon itself in convolute layers, the adjacent layers being cemented to each other on both surfaces, substantially as described.

5. A spinning and drawing roll having a 35 covering of artificial cork in thin sheet form wound upon itself in convolute layers, the adjacent layers being cemented to each other on both surfaces, and the inner layer being cemented to the rolls, substantially as described.

6. A spinning and drawing roll having a 40 covering composed of relatively thin sheets cut from artificial cork and wound upon each other in convolute layers, substantially as described.

In testimony whereof, I have hereunto set 45 my hand.

HERMAN F. BUSCH.
